UNITED STATES PATENT OFFICE.

SAMUEL MOORE, OF CLEVELAND, OHIO, ASSIGNOR OF ONE-HALF TO GAETANO MANGI-
ONE, TWENTY PER CENT TO ROBERT THOMAS WISE, EIGHT PER CENT TO E. A.
BAILEY, AND ELEVEN PER CENT TO JAMES D. MERIDA, ALL OF CLEVELAND, OHIO.

HOBBY HORSE.

Application filed October 19, 1927. Serial No. 227,284.

This invention relates to wheeled toys and provides an article which is adapted to be propelled and steered by the rider and which, when in motion, has an up and down movement imparted thereto.

The invention consists of a toy which may be cheaply constructed of wood, the body parts being cut from boards and assembled by being placed one against the other and secured by suitable fastening means.

While the drawing illustrates a preferred embodiment of the invention it is to be understood that in adapting the means to meet specific needs and requirements the design may be varied and such other changes in the minor details of construction may be resorted to within the scope of the invention as claimed, without departing from the spirit thereof.

For a full understanding of the invention and the merits thereof, reference is to be had to the following description and the drawing hereto attached, in which,—

Figure 1 is a side view of a hobby horse embodying the invention, a portion being broken away.

Figure 2 is a top plan view of the toy.

Figure 3 is a detail view showing the means for retaining the crank or pedal shaft in position.

Figure 4 is a detail view showing the means for retaining the axle in place.

Corresponding and like parts are referred to in the following description and designated in the several views of the drawings by like reference characters.

The body of the toy presents in outline the appearance of a horse and is formed of a plurality of similar sections placed one against the other and secured in any determinate way. In the preferable construction the body of the toy comprises an intermediate section or layer 1 and side sections or layers 2, the several sections or layers being cut from boards and placed one against the other and secured by wood screws 3, or analogous fastening means. The intermediate section or layer 1 is cut away to provide spaces 4 and 5 to accommodate the drive gearing. A post 6 is mounted in the forward portion of the body and is provided at its lower end with a fork 7, and at its upper end with a handle bar 8. A wheel 9 is mounted in the fork 7 and its axis 10

is eccentric and, as a result, the post 6 and forward portion of the toy receive and up and down movement during the travel of the toy forwardly, or backwardly. The post 6 is adapted to turn freely in the body of the toy, but is held against relative vertical movement.

The crank or pedal shaft 11 is mounted in the side sections 2 which are cut away at their lower edges to accommodate the shaft, as indicated most clearly in Figure 3. Filler pieces 12 close the lower ends of the openings and retain the shaft 11 in place. Each of the filler pieces 12 is formed with lateral extensions 13 in which wedge shaped openings are formed to receive the tapering ends of latches 14 whereby the filler pieces are held in place. The latches 14 are fitted in openings formed in the sections 2 and are normally urged into operative position by means of springs 15. The tapering ends of the latches 14 and the wedge-form of the openings formed in the extensions 13 insure retention of the filler pieces 12 in the openings closed thereby.

The axle 16 is mounted in openings formed in the lower ends of the leg portions of the side sections 2. The openings are closed by filler pieces 17 in substantially the same manner as the filler pieces 12. Spring catches 18 secured to the leg extensions of the body engage lateral extensions of the filler pieces 17 and hold them in place. A sprocket wheel 19 keyed to the axle 16 is connected by means of a sprocket chain 20 with a sprocket wheel 21 keyed to the crank shaft 11. The sprocket wheels are received in the respective spaces 4 and 5, and these spaces also accommodate the sprocket chain. The side sections 2 closing the spaces 4 and 5 form guards for the drive gearing and prevent the clothing of the rider coming in contact therewith. Wheels 22 are fitted to the ends of the axle 16.

Having thus described the invention, I claim:

1. A wheeled toy comprising a body formed of three sections arranged side by side and secured, the intermediate section having portions cut away to provide two spaces which are closed at their sides by the outer sections, the latter having edge portions cut away and forming openings to receive parts of the drive gearing, a crank

shaft and an axle extending across the respective spaces and mounted in the openings formed by the cutting away of the edge portions of the outer sections, filler pieces 5 closing the said openings and retaining the crank shaft and axle in place, sprocket wheels keyed to the crank shaft and axle, and disposed within the spaces formed by cutting away portions of the intermediate 10 section, and a sprocket chain connecting the sprocket wheels.

2. In a wheeled toy, a body having a por-

tion cut away to provide a space and having openings formed in the parts closing the sides of said space, a shaft received in the 15 said openings, filler pieces closing the openings and retaining the shaft in place, and having lateral extensions in which are formed wedge-shaped openings, and latches having tapering ends entering the wedge-shaped openings to retain the filler pieces 20 in place.

In testimony whereof I affix my signature.
SAMUEL MOORE. [L.s.]
